[57] CLAIM

The ornamental design for a spray bottle body, as shown and described.

DESCRIPTION

FIG. 1 is a front elevational view of a spray bottle body showing our new design, the rear and side views are identical;

FIG. 2 is a top plan view thereof;

FIG. 3 is a bottom plan view thereof; and,

FIG. 4 is a perspective view thereof.

The broken line showing of a collar and spray mechanism is for illustrative purposes only and forms no part of the claimed design.
